UNITED STATES PATENT OFFICE

PAUL F. GUTMANN, OF ST. LOUIS, MISSOURI, ASSIGNOR TO MISSISSIPPI GLASS COMPANY, OF ST. LOUIS, MISSOURI, A CORPORATION OF NEW YORK

APPARATUS FOR MAKING WIRE GLASS

Application filed October 9, 1930. Serial No. 487,408.

This invention pertains to the manufacture of sheet glass reinforced by wire mesh, and is particularly adapted to the manufacture of wire glass by the continuous process.

5 An object of the invention is to feed the wire mesh into the molten metal at a point close to a forming pass in order that the wire may be accurately positioned in the metal.

10 Another object is to reduce the distance the wire must travel in the molten metal before reaching the pass, in order to more accurately position the wire in the sheet.

15 Further and other objects and advantages will be apparent from the specification and claims, and from the accompanying drawings which illustrate what is now considered the preferred embodiment of the invention.

Fig. 1 shows a somewhat diagrammatic view of the invention.

20 Fig. 2 is a cross-section on the line 2—2 of Fig. 1.

Molten metal 10 flows from furnace 12 over lip 14 onto roll 16, to be carried thereby to the left under gate 18 by which a preliminary sheet 20 of predetermined thickness is formed. This sheet afterwards passes through the final forming pass between lower roll 16 and upper roll 22, to emerge therefrom as sheet 24, which is thereafter treated in the usual manner. Any surplus metal passing under gate 18 accumulates as a "ball" 25. The lip 14 and gate 18 form the discharge throat for the furnace and as clearly disclosed, these parts cooperate with the roll 16 to determine effectively the amount of metal discharged through the pass 16—18.

The reinforcing wire mesh 26 is fed by bristle roller 27 over bar 28 and guide fingers 30 into molten metal 10 at a point between lip 14 and roll 16, thence under gate 18 as part of the preliminary sheet 20, to finally emerge as part of sheet 24.

Bar 28 has a boss 32 lengthwise thereof, into which are inserted stems 34 of guide fingers 30. Bar 28 is adjustably supported at its ends by plates 36 attached to frame 38 by bolts 40 passing through slots 42 of brackets 36. Bar 28 is angularly adjustable in brackets 36 by means of set screws 44 and 46 threaded through ears 48 and 50 and abut-

ting opposite sides of boss 32. By this means bar 28 may be rotated to simultaneously position all guide fingers 30 in order to feed wire 26 into the molten metal 10 at any desired point.

55 By the use of a gate 18 to form the preliminary sheet, it is possible to place a forming pass much closer to lip 14 than is possible when a roll is used to form the pass, as will be readily apparent by comparison of the 60 relative shapes of gate 18 and roll 22 in the drawings.

From the above description it will be appreciated that fingers 30 support and guide the wire mesh to a point closely adjacent 65 metal 10 between lip 14 and roll 16, and that the wire almost immediately after leaving fingers 30 passes into control of the pass between gate 18 and roll 16.

The space between roll 16 and lip 14 is, of 70 course, restricted sufficiently to prevent flow of metal therethrough.

It is to be understood that the invention is not limited to the specific embodiment herein illustrated and described, but may be used in 75 other ways without departure from its spirit as defined by the claims which follow.

I claim—

1. In apparatus for forming reinforced wire glass, in combination, a rotatable roll, 80 a lip over which molten metal is fed onto the upper surface of said roll, a gate spaced above said roll cooperating therewith to form a pass between said gate and said roll, and means for guiding wire mesh between said 85 lip and roll into said metal and toward said pass, substantially as described.

2. In apparatus for forming reinforced wire glass, in combination, a rotatable roll, 90 a lip over which molten metal is fed onto said roll, a gate spaced from said roll to form a pass whereby a metal sheet of predetermined thickness is formed between said gate and said roll, and means between said lip and said roll for guiding wire mesh into said sheet 95 as said sheet is being formed, whereby a sheet of wire glass is formed supported by said roll.

3. In apparatus for forming reinforced wire glass, in combination, a rotatable roll, 100 a lip over which molten metal is fed onto

said roll, a gate spaced from said roll to form a pass whereby a metal sheet of predetermined thickness is formed between said gate and said roll, means between said lip and said roll for guiding wire mesh into said sheet as said sheet is being formed, whereby a sheet of wire glass is formed supported by said roll, and a second roll adjacent said first roll whereby a roll pass is formed between said rolls, to receive the sheet from the pass between the gate and roll.

4. In apparatus for forming sheet wire glass, in combination, a furnace having a discharge throat formed in part by a gate, a roll spaced from and cooperating with said gate to form a pass whereby a sheet of predetermined thickness is formed between the gate and roll, and means for guiding wire mesh directly into the metal discharged from said throat and into said pass.

5. In apparatus for forming sheet wire glass, in combination, a furnace having a discharge throat formed in part by a gate, a roll spaced from and cooperating with said gate to form a pass, a lip on the furnace forming a throat wall, and means for guiding wire mesh beneath said lip and into the metal between the roll and gate.

6. In apparatus for forming sheet wire glass, in combination, a furnace, a roll located below the discharge throat of said furnace, a gate spaced from and cooperating with said roll to form a pass and control the discharge of metal from the furnace whereby a sheet of predetermined thickness is formed between the gate and roll, and means for guiding wire mesh into the metal in said pass.

In testimony whereof I hereto affix my signature.

PAUL F. GUTMANN.
